[57] ABSTRACT

A fluid pump having a by-pass circuit comprising by-pass ports adjacent to the inlet and outlet zones of the pump, a flexible diaphragm and means biasing the diaphragm to close one or both of the by-pass ports and, thus, close off the by-pass circuit at least when the pump is at rest.

PUMP BY-PASS

BACKGROUND OF THE INVENTION

1. Field of the Invention

This invention relates to a fluid pump and, more particularly, to a by-pass circuit for such a pump.

2. Description of the Prior Art

The device of the present invention may be used on many forms of fluid pumps. However, the invention has been found to be especially advantageous when used with a rubber impeller pump such as disclosed in any one of the following U.S. Pat. Nos.: 2,782,723; 2,853,021; 2,858,769; 2,881,710; 2,971,469; 2,976,811; 3,303,791; 3,467,019.

For some applications, it is desired that there be provided a by-pass circuit for a fluid pump. An example of such an application is when a pump is used to pump wine through filter paper. A by-pass circuit is desired in this instance to provide a cushioning effect which will minimize a shock wave that could take place in such an application and, thus, eliminate or at least minimize the damage which might otherwise occur to the filter paper.

SUMMARY OF THE INVENTION

According to the principal aspect of the present invention, there is provided a fluid pump which is embodied with a by-pass circuit communicating with the inlet and outlet zones of the pump. The pump housing includes a wall which is formed with a pair of by-pass ports therein. A flexible diaphragm is biased against the wall to close one or more of the by-pass ports, thus closing off the by-pass circuit, at least when the pump is at rest.

BRIEF DESCRIPTION OF THE DRAWINGS

FIG. 1 is a partial longitudinal sectional view through a fluid pump embodying the by-pass circuit of the present invention;

FIG. 2 is a front elevation of the pump housing wall embodying the by-pass ports;

FIG. 3 is a transverse sectional view taken along line 3-3 of FIG. 1; and

FIGS. 4 and 5 show the performance characteristics of the pump of the present invention.

DESCRIPTION OF THE PREFERRED EMBODIMENT

Referring now to FIGS. 1-3 in detail, there is illustrated a fluid pump, generally indicated 10, which embodies the by-pass circuit of the present invention. The pump includes a housing 12 providing a chamber 14 for a rubber impeller 16 having a hub 18 and radial vanes 20 adapted to be flexed in the usual manner by a cam 22. The housing 12 consists of an intermediate ring section 24 closed at its opposite ends by plates 26 and 28. Extending into the chamber 14 is a shaft 30 driven by any suitable means, such as a motor 32.

The end 34 of the shaft 30 in the chamber 14 is externally splined to engage internally splined bushing 36 to which the hub 18 of the rotor is sealed. A suitable shaft seal 40 prevents leakage of pump fluid along the pump shaft.

As best seen in FIG. 3, the pump housing 12 includes inlet and outlet ports 42 and 44, respectively. The areas

of the pump chamber 14 adjacent to ports 42 and 44 define inlet and outlet zones 46 and 48 therein.

The portion of the pump 10 described so far is generally conventional and constitutes no part of the present invention, the latter being a by-pass circuit, generally designated 50. The by-pass circuit may be applied to any form of pump, the vane type pump described herein being given by way of example only. The by-pass circuit comprises an enclosure 52 secured to the end plate 26 of the pump by bolts, not shown. The enclosure is formed with a recess 54 and vent passage 55. The plate 26 is formed with by-pass ports 56 and 58 which communicate with the pump chamber 14 adjacent the inlet and outlet zones 46 and 48, respectively.

15 It will be understood, however, that the ports 56 and 58 could be angularly offset from the respective angular positions of the inlet and outlet zones of the pump provided that in use by-pass flow will be established.

20 When the pump is at rest, the ports 56 and 58 are closed by a flexible rubber diaphragm 60. The outer region of the diaphragm is bonded by an adhesive to an annular recess 62 in the face of the enclosure 52. A circular thrust pad 64 is positioned adjacent to the diaphragm 60. The pad carries an axially extending pin 66 which is surrounded by coil spring 68. The enclosure 52 is formed with an externally threaded boss 70 which is formed with an inwardly directed flange 72 against which one end of the spring 68 abuts. The other end of the spring engages the pad 64 thereby urging the diaphragm 60 against the surface of the end plate 26 thereby closing the ports 56 and 58.

25 An internally threaded adjustment knob 74 is threadably engaged on the boss 70. The knob 74 acts as a stop member for the end 76 of the pin 66 which extends through an aperture 78 in the end of the boss. A rod 80 is press fitted in a vertically extending passage 82 in the knob 74 to facilitate rotation thereof.

30 When the pump starts, fluid pressure in the pump chamber 14 will create a pressure on the pumpside of the diaphragm 60 but cannot move the diaphragm away from the end plate 26 of the pump housing because the pin 66 and thrust pad 64 hold the diaphragm against movement. When the knob 74 is unscrewed 35 slightly, the fluid pressure in pump chamber 14 will overcome the force of the spring 68 to move the diaphragm away from the plate 26 to form a by-pass chamber therebetween, and a by-pass flow will start, thus reducing the flow of liquid through the pump. The by-pass flow can be adjusted by the knob 74.

35 Although not shown, it is conceivable that means can be provided for altering the compression force of the spring 68.

40 It will be appreciated that the diaphragm 60 will close upon the by-pass ports 56 and 58 when the pump is at rest. This enables the pump to be automatically self-priming.

45 The by-pass circuit 50 could be arranged to act as a safety device, by being arranged to come into action only in the event of undue pressure build-up in the pump.

50 It is possible that the diaphragm will, when the control knob 74 is positioned to allow a by-pass flow, provide a cushioning effect which may minimize a shock wave which can take place in certain installations, for example, when the pump is used to pump wine through filter paper. The chance of damage which might other-

wise occur can thus be eliminated or at least minimized.

FIGS. 4 and 5 show performance curves of, respectively, a Jabsco-type 11640 pump and Jabsco-type 21000 pump, each fitted with a by-pass circuit substantially as described herein. Such Jabsco pumps are manufactured by ITT Jabsco, Costa Mesa, California. In each figure, curve A represents the performance with the by-pass circuit closed. Curve B represents the performance with the diaphragm movement at a maximum, that is, full by-pass flow.

In a typical filtration system, it is important that pump characteristic is selected to suit the filter or filters being used. If pump flow is considerably in excess of the nominal filter capacity giving high fluid velocity, probably inadequate filtration and damaging of the filter elements may occur. Therefore, the pump flow should be reduced by throttling the inlet valve (not shown), or opening the by-pass 50 or a combination of these two techniques.

Although I have herein shown and described my invention in what I have conceived to be the most practical and preferred embodiments, it is recognized that departures may be made therefrom within the scope of my invention which is not to be limited to the details disclosed herein but is to be accorded the full scope of the claims so as to embrace any and all equivalent structures and devices.

What is claimed is:

1. A fluid pump having a by-pass circuit comprising: 30

a pump housing having a chamber therein and inlet and outlet ports communicating with inlet and outlet zones, respectively, within said chamber; a pump member mounted for rotation in said chamber about an axis; 35 said housing including an end wall perpendicular to

said axis; inlet and outlet by-pass ports extending through said end wall generally parallel to said axis, said by-pass circuit including said by-pass ports; a flexible diaphragm in juxtaposition with the outer surface of said end wall and extending over said by-pass ports; and means biasing said diaphragm into engagement with said end wall to close said by-pass ports at least when the pump member is at rest.

2. A fluid pump as set forth in claim 1 wherein: said housing includes a ring section surrounding said pump member; and said inlet and outlet ports are provided on said ring section.

3. A pump as set forth in claim 1 including: a thrust pad engaging the surface of said diaphragm opposite to said end wall, said pad carrying a rigid projecting pin extending parallel to said axis; said biasing means engaging said thrust pad; and screw threaded means directly engaging the free end of said pin, said threaded means being movable, by screwing, to increase and decrease the limit of diaphragm movement.

4. A pump as set forth in claim 1 including: by-pass flow adjustment means for controlling the flow of fluid through said by-pass ports.

5. A pump as set forth in claim 1 including: an enclosure for said diaphragm attached to said housing; and said diaphragm being sealed in a fluid-tight manner along its peripheral region to said enclosure.

6. A pump as set forth in claim 1 wherein: said by-pass ports are located adjacent to said inlet and outlet zones.
